UNITED STATES PATENT OFFICE

2,458,739

MECHANICAL PENCIL WITH LEAD STORAGE
UNIT

Mark E. Savoie, Cleveland, Ohio

Application August 25, 1945, Serial No. 612,590

2 Claims. (Cl. 120—14.9)

1

My invention relates in general to new and useful improvements in mechanical lead pencils and more particular in those mechanical pencils which have a lead propel mechanism, a lead storage magazine, and an eraser propel and retract mechanism incorporated within the barrel of the pencil.

An object of my invention is the provision of a lead feeding mechanism and a storage magazine with the lead storage magazine slidably and removably mounted within one end of the barrel of the mechanical pencil for holding the lead feeding mechanism.

Another object of my invention is the provision of certain improvements in mechanical pencils of the type having an eraser propel and retract mechanism on one end thereof and a lead propel mechanism on the other end thereof with a lead storage magazine therebetween.

Another object of my invention is the combination of a lead storage magazine and a lead feed mechanism in which the extra lead may be stored about the feeding screw sheath portion of the lead feeding mechanism.

A further object of my invention is the provision of a lead storage magazine in a lead propel mechanical pencil with cooperating means whereby the storage magazine and the lead propel or feeding unit may be removed from the barrel to obtain a lead from the extra supply of lead.

Other objects and a fuller understanding of my invention may be had by referring to the following description and claims, taken in conjunction with the accompanying drawing, in which:

Figure 1 is a perspective view of a preferred embodiment of my mechanical lead pencils;

Figure 2 is a cross-sectional view of Figure 1 showing the features of my invention;

Figure 3 is a perspective view illustrating the use of the lead feeding tip in removing the lead storage magazine from the barrel of the mechanical pencil;

Figure 4 is a fragmentary view of my lead storage magazine illustrating the support member which supports the lead feeding tip;

Figure 5 is a modification of Figure 4;

Figure 6 is a cross-sectional view taken along the line 6—6 of Figure 2; and

Figure 7 is a perspective view in reduced scale of the closure cap used in my lead storage magazine.

Manufacturers have generally sacrificed the size of an eraser used in a mechanical pencil to enable them to have a lead storage magazine for extra leads. In my invention, I have provided a

2

means for having a lead storage magazine within the barrel of the pencil and still having a large supply of erasing material without increasing the length of the pencil over that of standard mechanical pencils. In my mechanical pencil the lead storage magazine is mounted within the end of the barrel and supports the lead feeding mechanism. The space about the lead propelling screw sheath within the barrel is utilized to store extra leads 27. These leads may be removed from the lead end of the pencil without disturbing the eraser mechanism.

As shown in the accompanying drawings, and in particular Figures 1 and 2, my mechanical pencil 10 comprises in general a pencil barrel which has a propel and retract eraser mechanism 12 on one end thereof and a lead feeding mechanism and a lead storage magazine on the other end thereof. Extra leads 27 are carried in the storage magazine. For purposes of reference and clarity in my description and the accompanying claims, I have designated that end of the barrel which supports the eraser mechanism 12, as the eraser end 15, and that end of the barrel which supports the lead storage magazine 14 and the lead feeding mechanism 13 as the lead end 16 of the barrel. The lead storage magazine 14, which is slidably mounted within the barrel supports the lead feeding mechanism 13. The eraser mechanism 12, as illustrated in the drawings Figure 2, is fully described under the application filed concurrently herewith by the same inventor and entitled "Eraser holding mechanism." However, it is understood that any suitable eraser mechanism may be used in the pencil without departing from the scope of the invention as set forth in this application.

In the preferred embodiment of my invention, the lead storage magazine is constructed from a cylindrical shell 23 which has an open end 21 and a closed end 22. A closure cap 24, which may be inserted in the open end of the shell, prevents the extra leads 27 from leaving the storage magazine while it is inserted in the pencil barrel. The closed end of the shell 22 has a support member 25 which externally supports the cylindrical shell and internally supports a lead feeding screw sheath 26. The support portion or support member 25 has an annular flange thereabout and intermediate the ends thereof. The fastening portion 31, on one side of this annular flange, engages the closed cylindrical shell 23 for supporting the same. The shell 23 may be fastened to the support member by a press-fit or by other suitable means, such for

example soldering. The external support portion 30, on the other side of this annular flange 28 freely projects into the lead feeding tip 36. The outer diameter of the cylindrical shell 23 is substantially equal to the inner diameter of the barrel 11 to provide a frictional engagement therebetween.

The lead feeding screw sheath has an elongated tubular portion 32 and a non-circular portion 33. I have provided an opening 29 in the center of the support member 25. The elongated tubular portion 32 of the lead feeding screw sheath extends through this opening and is fastened thereto by a press-fit or other suitable means, such for example, soldering. The elongated tubular portion 32 as shown in Figure 2, has an opening 34 in the wall thereof. The lead feeding mechanism 13 is supported by the elongated tubular portion 32. This support results from the fact that the sleeve 37 is frictionally insertable into the tubular portion 32, whereby the feeding mechanism may be pulled off for inserting a new lead and whereby the tip 36 may be turned with respect to the barrel. The non-circular portion is that portion which is enclosed within the cylindrical shell 23. As is shown in the Figures 2 and 6, the actual storage space within the lead storage magazine is the space about the non-circular portion 33 of the lead feeding screw sheath 26.

My lead feeding mechanism 13 includes a lead feeding tip 36 which has an internally threaded lead feeding screw sleeve 37 and a lead propelling screw 38. The lead feeding tip 36 may be of any suitable type known in the art of mechanical pencils. In Figure 2, I show the lead propelling screw threaded partially through the internally threaded lead feeding screw sleeve 37 and supporting a lead 39 in writing position in the split tip 40.

To assemble one of my pencils, the lead storage magazine 14 is first slipped into the end of the barrel and then the lead feeding tip 36 is fitted onto the external end of the lead storage magazine. The flange 28 bumps against the end of the barrel to prevent the storage magazine from being pushed farther therein. Similarly, the end of the lead feeding tip 36 engages the flange 28, thus making an externally neat appearing article of manufacture. While the component parts of the pencil are in this position, the internally threaded lead feeding screw sleeve 37 extends into the elongated tubular portion 32 of the lead feeding screw sheath 26. The lead propelling screw extends upwardly into the non-circular portion 33 of the screw sheath 26.

I have designed a hook 46 on the end of the lead propelling screw which extends into the lead feeding screw sheath 26. The purpose of this hook is twofold. One purpose is to provide cooperating means between the screw and the screw sheath for preventing rotational movement therebetween. The sheath 26 is kept from turning with respect to the barrel 10 by the friction between the barrel and the magazine which supports the sheath. The friction between the sheath 26 and the barrel is greater than the friction between the elongated tubular portion 32 and the lead feeding sleeve 37. The operator of the pencil thus may propel lead from the feeding tip of the pencil by merely turning the feeding tip with respect to the barrel.

The second use of the hook 46 on the end of the lead propelling screw 38 is most clearly shown in Figure 3. Here the lead storage magazine is shown partly removed from the end of the barrel.

To remove the lead storage magazine from the barrel, the operator first pulls the lead feeding tip 36 off the end of the pencil and then engages the hook 46 into an opening 34 provided in the external elongated tubular portion 32 of the lead feeding screw sheath 26. The next operation is simply to pull the lead storage magazine from the end of the barrel. After the magazine has been removed, the hook may be used to remove the cap 24 from the open end of the shell 21 to obtain another lead. I have illustrated this cap in Figure 7 as having an opening 55 in the center and an opening 56 on the corner thereof to provide means for the hook to engage the cap. However, it is understood that any suitable cap or closure means may be used to enclose the end of this shell.

In Figure 5, I illustrate the use of a modified form of the support member 25 and the elongated tubular portion 32 of the lead feeding screw sheath 26. In this modification, the support member 49 has a cone-shaped external portion 52. The purpose of the cone-shaped portion is to bring the surface from the diameter of the cylindrical shell to more nearly the diameter of the elongated tubular portion and at the same time provide a surface which may be gripped by the fingers. To also enlarge this finger-gripping surface, I have elongated the tubular portion of the lead feeding screw sheath as is designated by number 53 in my drawings. The purpose of this modification is to eliminate the necessity of hooking the screw into an opening in the sheath to pull the lead storage magazine from the barrel. By providing the finger-grip surface, it is possible to pull the magazine from the barrel with the fingers.

Although I have described my invention in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

This application is a continuation-in-part of my application Serial No. 559,037, filed October 17, 1944 now abandoned.

What is claimed is:

1. A removable lead storage unit for a pencil barrel having an opening in the end thereof and an end surface about said opening, said lead storage unit comprising an elongated cylindrical tube adapted to be frictionally and slidably inserted in the said pencil barrel and having an inner open end and an outer open end, a support member fitted nonremovably in the outer open end to close said end of the tube, said support member having external flange stop means engageable with the end surface of the pencil barrel to limit movement of the elongated cylindrical tube into the pencil barrel, said support member also being provided with an opening therethrough and extending co-axially therewith, and a sheath having a cylindrical portion anchorably fitted in the opening in the support member and also having a noncylindrical portion thereof extending co-axially with and disposed within the cylindrical tube, the space within the cylindrical tube and outside of the noncylindrical portion of the sheath constituting a storage space for leads, the cylindrical portion of the sheath extending outwardly beyond the support member and the cylindrical tube for providing

an engagement means for readily removing the support member and the cylindrical tube from the pencil barrel for access to the stored leads therein.

2. A removable lead storage unit for a pencil barrel having an opening in the end thereof and an end surface about said opening, said lead storage unit comprising, an elongated support tube adapted to be frictionally and slidably inserted in said pencil barrel and having an inner open end and an outer open end, a sheath axially disposed within the elongated support tube, a closure member fitted nonremovably in the outer open end of the elongated support tube and carrying said sheath, said elongated support tube, said sheath and said closure member constitute a removable unitary structure with the space outside of the sheath and within the elongated support tube providing a magazine storage space for leads and with the inner open end of the elongated support tube providing access into the lead storage magazine, said closure member hav-

ing an external flange abuttable against the end surface of the pencil barrel to limit movement of the unitary structure into the pencil barrel and also having an opening extending co-axially therethrough, said sheath having an anchoring portion anchorably fitted in the opening in the closure member and extending outside the closure member and beyond the elongated supporting tube for providing engagement means for readily removing the unitary structure from the pencil barrel for access to leads stored therein.
